COMBINATION TOY

Henry F. Benze, Emmett, Nebr.

Application September 30, 1946, Serial No. 700,285

5 Claims. (Cl. 155—41)

1

This invention relates to a combination toy and has for its primary object to afford entertainment and amusement for children.

Another object is a toy which is convertible from a hobby horse, into a tricycle and also into a wagon.

A still further object of the invention is to afford variations in appearance of the tricycle so that when it is used as a tricycle, or as a hobby horse the contour thereof may be changed to afford variety.

The above and other objects may be attained by employing this invention which embodies among its features, a pair of side boards, one edge of each side board being curved longitudinally to form a rocker, a pair of removable axles extending between the side boards to hold the curved edges thereof in spaced relation, and a wheeled carriage demountably supported between the straight edges of the side boards to form a seat upon which a child may sit and rock.

Other features include a steering column on the tricycle, a hand hold detachably connected to the steering column whereby different contours of hand holds may be substituted, and means carried by the tricycle detachably to mount the tricycle on the side boards when the tricycle is to be used as a hobby horse.

Still further features include turning the rear axle of the tricycle so that it will extend longitudinally of the body thereof to fit between the side boards, or turning the axle to extend transversely of the body thereof and a wheel detachably mounted on the axle to permit such turning and means carried by the tricycle to support the wheel when it is detached from the axle.

Still other features include a bottom board hinged to each side board adjacent the straight edge thereof, axles extending between the side boards, means carried by the axles for engaging opposite ends of the bottom boards and end boards detachably mounted between the side boards and resting on the bottom boards to form a wagon, and wheels on the axles.

In the drawings:

Figure 1 is a perspective view of a combination toy embodying the features of this invention showing the same assembled to produce a hobby horse,

Figure 2 is a longitudinal sectional view taken substantially along the line 2—2 of Figure 1,

Figure 3 is a perspective view of the combination toy assembled to produce a wagon,

Figure 4 is an end view of Figure 1,

Figure 5 is a perspective view of a modified form of hand hold,

2

Figure 6 is a perspective view of the tricycle illustrating a further modified form of hand hold in place thereon,

Figure 7 is a top plan view of Figure 3,

Figure 8 is an end view of Figure 3,

Figure 9 is a perspective view of one of the axles, and

Figure 10 is a bottom plan view of the tricycle.

Referring to the drawings in detail, this improved toy comprises a pair of side boards 15 each of which is provided with a longitudinally curved edge 16 and a straight edge 17. Formed in the side boards near the curved edges are longitudinally spaced openings 18 (Figure 3) the purpose of which will be more fully hereinafter explained. Formed in the side boards 15 adjacent opposite ends, and extending perpendicular to the straight edges 17 thereof are grooves 19 (Figure 3) the purpose of which will more fully hereinafter appear. Secured to the side boards adjacent the straight edges 17 thereof are hinges 20 to which bottom boards 21 are secured in such a manner that when the device is in use as a hobby horse these bottom boards will lie against the inner sides of the side boards 15 as will be readily understood upon reference to Figure 4.

A component part of this toy comprises a tricycle designated generally 23 which is formed of a base-board 24 carrying a back 25 and side arms 26 to form a seat upon which a child may rest. The bottom 24 is cut-away at opposite sides as at 27 (Figure 6) to accommodate the child's legs, and pivotally supported adjacent the end of the board 24 opposite the seat is a steering column 28, the upper end of which is bifurcated as at 29 to receive the lower end of a hand hold designated generally 30. As illustrated, the hand holds 30 may be made in any suitable design, for instance, as a steering wheel 31, a duck's head 32 or a horse head 33. In the event that the duck's head or horse head is employed, each is provided with a laterally extending hand-grip 34 which may be grasped by the hands of the occupant of the seat to provide a handle bar by means of which the tricycle may be steered. A suitable traction wheel 35 is mounted in the lower end of the steering column 28 and equipped with suitable crank arms 36 carrying pedals 37 by means of which the tricycle 23 may be propelled.

Pivotedly supported as at 38 (Figure 10) beneath the seat of the tricycle is the rear axle 39 thereof to opposite ends of which are detachably connected wheels 40 and 41. These wheels are preferably held in place by suitable cotter pins

42 so that one or the other of the wheels may be demounted from the axle to permit it to be moved about the pivot 38 so as to lie in a plane longitudinally of the tricycle. As seen best in Figures 2 and 10 suitable friction member 42 projects downwardly from the underside of the pivot 38 and serves as a support for the wheel 41 when the axle is moved into its longitudinally extending position. A suitable substantially U-shaped spring 43 is carried by the underside of the base-board 24, and is adapted when the axle 39 extends crossways of the longitudinal axis of the tricycle to engage the side edge thereof and hold the axle in proper position for use. Attached to the member 24 adjacent its forward ends are supporting brackets 44 each of which extends laterally from the member 24 and is provided with an eye 45 the purpose of which will be more fully hereinafter explained. Pivotally supported adjacent the rear end of the member 24 and immediately behind the back 25 of the seat are supporting brackets 46 which like the brackets 44 are provided with eyes 47 the purpose of which will more fully hereinafter appear.

Axes designated generally 48 (Figure 9) are provided at opposite ends with circular cylindrical extensions 49 upon which wheels 50 are detachably mounted as by cotter pins 51. Each axle 48 comprises an elongated body 52 of substantially rectangular cross-section to form shoulders 53 at opposite ends, and extending longitudinally of each axle member 52 is a Z-bar 54 the purpose of which will more fully hereinafter appear.

The web of each Z-bar 54 is provided adjacent opposite ends with elongated slots 55 by a purpose to be more fully hereinafter explained.

End boards 56 which when the device is used as a wagon as illustrated in Figure 3 fit in the grooves 19, carry adjacent opposite ends angularly extending hooks 57 which are adapted when the boards are used as above described to engage in eyes 58 carried by the side boards 15 near the grooves 19. Suitable eyes 59 are carried at opposite ends of the bottom boards 21 and are adapted to project through the slots of the Z-bars 54 to hold the bottom boards in proper position when the device is constructed to produce a wagon, and extending through the eyes 59 are the hook ends 60 of a twisted wire tongue 61.

When the device is to be used as a wagon as illustrated in Figure 3, the tricycle 23 is not employed in the construction of the wagon. The bottom boards 21 are swung on their hinges 20 to extend perpendicular to the side boards and the axles 48 are placed beneath the straight edges 17 of the side boards in such a manner that the top flange of each Z-bar 54 overlies a portion of the end of each bottom board 21, (see Fig. 2), with the side boards 15 engaging the ends of the Z bars. In this position the eyes 59 will project through the slots 55 and may be held in this position by extending the hooks 60 of the tongue 61 through the eyes. The wheels 50 are then mounted on the axles 48 and held in place on the cylindrical extensions 49 thereof by means of the cotter pins 51. The end boards 56 are then introduced into the grooves 19 so that the hooks 57 will engage in the eyes 58, and thus hold the side boards in proper position on the axles, to form a wagon.

A suitable substantially U-shaped spring clip 62 (Figure 7) is introduced into the eyes 60 at the end of the wagon opposite the tongue 61 in order securely to lock the parts together.

When the device is to be used as a hobby horse, the cylindrical extensions 49 are projected through the openings 18 in the side boards 15 with the curved edges 16 of the side boards turned downwardly. The tricycle 23 is introduced between the straight edges of the side boards as illustrated in Figure 1 with the brackets 44 and 46 resting on the straight edges 17 to support the tricycle in position to provide a convenient seat. Suitable eyes 63 project outwardly from the side boards 15 adjacent the straight edges 17 and are extended through the openings 45 and 47 of the brackets 44 and 46 respectively, and a suitable locking bolt 64 is extended through the eyes as illustrated in Figure 1 securely to hold the tricycle in place.

In order to support the spare parts suitable spring clips 65 are located at convenient points on the inner sides of the side boards 15 and are shaped to conform to the contours of the parts which they are adapted to engage.

From the foregoing, it will be seen that an unusually versatile toy is provided which may be utilized in various different ways to afford entertainment and amusement for children, and a child who may be mechanically inclined may have the pleasure of constructing the various different items, and interchanging the parts to suit his desires.

While in the foregoing there has been shown and described the preferred embodiment of this invention it is to be understood that minor changes in the details of construction, combination and arrangement of parts may be resorted to without departing from the spirit and scope of the invention as claimed.

I claim:

1. In a collapsible toy cart a pair of side boards, the top edge of each side board being curved longitudinally, a bottom board hinged to each side board adjacent the straight edge thereof, axles extending between the side boards, means carried by the axles for engaging opposite ends of the bottom boards and end boards detachably mounted between the side boards and resting on the bottom boards.

2. In a toy a pair of side boards, one edge of each side board being curved longitudinally to form a rocker, means to hold the side boards in spaced relation, a wheeled carriage demountably supported on the straight edges of the side boards, an axle pivotally mounted on the carriage to move through an arc of 90° degrees and wheels on the axle at least one of which may be removed from the axle to permit the axle to extend longitudinally between the side boards when the carriage is in position on the side boards.

3. In a combination toy, a pair of side boards, one edge of each side board being curved longitudinally to form a rocker, means extending between the side boards to hold them in spaced relation, a wheeled carriage demountably supported between the straight edges of the side boards, an axle pivotally mounted on the carriage to move through an arc of 90°, wheels on the axle at least one of which may be removed from the axle to permit the axle to extend longitudinally between the side boards when the carriage is in position on the side boards, a post on the carriage, an interchangeable hand-hold secured detachably to the post, and means to detachably secure the carriage on the side boards.

4. A collapsible toy comprising a pair of side boards, said side boards having a straight edge

and a curved edge, detachable means for supporting said side boards in spaced relation and adapted to be provided with wheels, vertical grooves on said side boards adapted to receive end boards, removable child supporting means mounted on said side boards, said supporting means comprising a seat portion, a steering column positioned on said seat portion, a hand hold removably mounted on said steering column, said handhold adapted to be interchangeable with a plurality of hand holds removably mounted on said side boards.

5. A collapsible toy comprising a pair of side boards, said side boards having a straight edge and a curved edge, detachable means for supporting said side boards in spaced relation and adapted to be provided with wheels, vertical grooves on said side boards adapted to receive end boards, removable child supporting means mounted on said side boards, said supporting means comprising a seat portion, a steering column positioned on said seat portion, a hand hold removably mounted on said steering column, rotatable means on said supporting means, said rotatable means being provided with pedal means whereby a child sitting on the supporting means can rotate said rotatable means.
